UNITED STATES PATENT OFFICE.

HARRY E. NORVIEL, OF ANDERSON, INDIANA, ASSIGNOR TO DELCO-REMY CORPORATION, OF DAYTON, OHIO, A CORPORATION OF DELAWARE.

ELECTRIC SWITCH.

Application filed April 12, 1927. Serial No. 183,142.

This invention relates to electrical switches and particularly to switches adapted to be operated by the brake pedal of an automobile for the purpose of closing a circuit to a stop lamp or other indicator at the rear end of the vehicle.

One of the objects of the present invention is to provide a brake pedal operated switch which is very compact and durable in construction and which will provide for such movements of its contacts as are necessary to maintain a circuit closed during the major portion of the movement of the brake pedal.

Further objects and advantages of the present invention will be apparent from the following description, reference being had to the accompanying drawings, wherein a preferred form of embodiment of the present invention is clearly shown.

In the drawings:

Fig. 1 is a plan view partly in section of a switch embodying the present invention, the section being taken on the line 1—1 of Fig. 2;

Fig. 2 is a side view partly in section of the switch shown in Fig. 1, this view looking in the direction of the arrow 2 of Fig. 1;

Fig. 3 is a sectional view on the line 3—3 of Fig. 4 and shows the movable contact in one of its circuit closing positions;

Fig. 4 is a sectional view on the line 4—4 of Fig. 3;

Fig. 5 is a view similar to Fig. 3 showing the movable contact in another of its circuit closing positions;

Fig. 6 is a sectional view on the line 6—6 of Fig. 5;

Fig. 7 is a detail view of the non-conducting plate for carrying a movable contact;

Fig. 8 is a detail view of a member for drivingly connecting the contact carrying element shown in Fig. 7 with an operating shaft; and

Fig. 9 is a fragmentary side elevation of the switch case looking in the direction of the arrow 9 in Fig. 2.

Referring to the drawings, 20 designates a box-like case having its top wall 21 attached to a bracket 22 by which the switch may be mounted upon some part of the automobile chassis. The case 20 is provided with a removable bottom plate or cover 23 which is secured in any suitable manner. An oblique side wall 24 insulatingly supports conducting

rivets 25 having tapped central holes for receiving terminal screws 26. Each rivet 25 is accordingly connected with and secures to the wall 24 the base portion 27 of an electric contact 28. Each contact 28 is made of flexible sheet material and comprises a shank or bracket 29 extending from the base 27 to an arcuate contact element which is concentric with respect to an operating shaft 31 supported by side walls 32 and 33 of the switch case 20. The bracket portion 29 is formed to provide an arc-shaped or substantially angular member having the extremities thereof joined to the base portion 27, and to the contact 30, respectively, with the intermediate portion thereof disposed in an adjacent part of the housing. This structure provides for the maximum amount of flexing of the contact and brackets without subjecting either of them to probable rupture through cooperation with the movable contact and its carrier.

The shaft 31 is provided near its central portion with diametrically opposite ridges 34 which serve as keys to drivingly connect the shaft 31 with a non-conducting contact support 35. As shown particularly in Fig. 7, the contact support 35 is provided with an aperture 36 shaped to receive the shaft 31 and having notches 37 each for receiving one of the shaft splines or keys 34. In order to reinforce the driving connection between the shaft 31 and the contact support 35, there is provided a metal reinforcing plate 40 having an opening 41 shaped like the opening 36 in the part 35. The member 40 includes arms 42 which are adapted to be bent into notches 43 provided by the part 35, after these parts have been assembled upon the shaft 31 as shown in Figs. 1 and 3 of the drawings.

The contact carrier 35 is at all times located between the arcuate contact portions 30 of the spring conductors 28, and carries a double headed contact rivet 44 normally out of engagement with the arcuate contacts 30 but adapted to provide an electrical connection between them when the carrier 35 is rotated in a clockwise direction as viewed in Figs. 2, 3 and 5.

The shaft 31 is attached to a lever 50 having a surface 51 adapted to be engaged by a lever 52 which is pivoted upon the shaft 31 but is not directly connected with it. The

lever 52 is adapted to be connected with the brake pedal of the automobile in any suitable manner. The shaft 31 is attached also to a lever 53 which is adapted to be operated by mechanism controlled by the transmission gear shift lever in such manner that when the gear shift lever is moved into reverse position the lever 53 will be operated to cause the switch to be closed. The system of operating levers is not of itself a part of the present invention but is described and claimed in the copending application of Harry C. Doane, Serial No. 198,339, filed June 13, 1927.

15 The shaft 31 is urged in a counterclockwise direction by a spring 60 having helical spring coils 61 surrounding the shaft 31 and joined by an intermediate loop 62, a portion of which passes through a notch 63 provided by the 20 contact carrier 35. The spring 60 is so biased that its central loop 62 tends to move in a counterclockwise direction as viewed in Figs. 2, 3 and 5, and the ends 64 of the spring 60 are retained in bayonet notches 65 extending 25 from the bottom edge 66 of the side 67 of the switch case as shown in Figs. 4, 6 and 9. The spring ends 64 tend to move downwardly as viewed in Fig. 9 but are restrained by virtue of their engagement with the portions 68 30 of the wall 67 which are adjacent the bayonet slots 65. The spring ends 64 are biased so that they tend to approach each other. In this way the spring ends are resiliently maintained within the slots 65. This construction avoids the necessity of using the cover 23 to maintain the spring ends in position; therefore the cover 23 may be removed without interfering with the operation of the 35 spring.

40 A slight clockwise movement of the shaft 31 will bring the movable contact 44 into engagement with the arcuate contacts 30 and will cause the arcuate contacts to take the position shown in Fig. 4 in which their lower ends 30^a are moved apart while their upper ends 30^b are moved together. This movement of the contacts 30 can take place with very little bending of the contact supporting bracket 29. As the shaft 31 continues to move 45 in a clockwise direction, the movable contact 44 will move in a circular path to the position shown in Fig. 5. When contact 44 is in this position the upper portions 30^b of the contacts 30 will be spread apart by the contact 44 while the contact portions 30^a will approach each other. The movement of the contacts 30 from the position shown in Figs. 3 and 4 to the position shown in Fig. 5 is accompanied by a slight twisting movement 50 of the shank 29 but the bending of the shank 29, especially the portions thereof adjacent their bases 27, has been reduced to a minimum. This construction of the contacts of the switch permits such movement of the 55 movable contact as is required due to its con-

nection with the brake pedal of the vehicle, without bending the spring conductors of the switch to such extent as to exceed their elastic limit. In other words, the stationary contacts of the switch are so constructed and arranged that they will accommodate a relatively great angular movement of the movable contact without causing any part of a stationary contact to be unduly strained so that it would not return to its normal position after the movable contact has been retracted.

It is therefore apparent that from the foregoing description of the construction and mode of operation of the present invention that there has been provided a switch of very durable and compact construction and suitable for operation by the brake pedal of an automobile for controlling a circuit to a stop light or other rear end signal.

While the form of embodiment of the present invention as herein disclosed, constitutes a preferred form, it is to be understood that other forms might be adopted, all coming within the scope of the claims which follow.

What is claimed is as follows:

1. An electric switch comprising contacts, one movable relative to the other, one of the contacts being elongated so that engagement between the contacts will be maintained during a substantial part of said relative movement; and a substantially angular shank readily capable of twisting movement for supporting the elongated contact in order that the elongated contact may readily tilt laterally relative to the plane of said relative motion while engaging the other contact.

2. An electric switch comprising contacts, one movable relative to the other, one of the contacts being elongated so that engagement between the contacts will be maintained during a substantial part of said relative movement; and a substantially angular contact supporting part attached to the elongated contact between its ends and readily capable of twisting movement in order that the elongated contact may readily tilt laterally relative to the plane of said relative motion while engaging the other contact, the ends of the elongated contact being displaced respectively in opposite directions as relative movement between the contacts takes place.

3. An electric switch comprising contacts, one movable relative to the other, one of the contacts being elongated so that engagement between the contacts will be maintained during a substantial part of said relative movement; and a substantially angular torsionally relatively flexible leaf spring part fixed at one end and connected at the other to the elongated contact and adapted to twist readily in order that the elongated contact may readily tilt laterally relative to the plane of said relative motion while engaging the other

contact and so that the bending of the leaf spring part about its fixed support will be minimized.

4. An electric switch comprising contacts, one movable relative to the other, one of the contacts being elongated so that engagement between the contacts will be maintained during a substantial part of said relative movement; and a torsionally relatively flexible leaf spring shank of angular formation fixed at one end and connected at the other to the elongated contact intermediate its ends so that when, due to the engagement of one end of the elongated contact with the other contact, that end of the elongated contact will be displaced laterally in one direction with respect to the plane of the relative movement between the contacts and the other end of the elongated contact will be displaced laterally in the opposite direction.
5. An electric switch comprising a pair of juxtaposed, spaced elongated contacts, a third contact for electrical connection with the pair of contacts by concurrently engaging them; means for producing relative movement between the pair of contacts and the third contact; and torsionally relatively flexible members of angular formation supporting the elongated contacts so that as relative movement between the third contact and the elongated contacts takes place, relative lateral displacement between the pairs of end portions of the elongated contacts will take place respectively in opposite directions.

6. An electric switch comprising a pair of 35 juxtaposed, spaced elongated contacts, each one having integral therewith and extending from an intermediate portion thereof a torsionally relatively flexible leaf spring shank of angular formation fixed at the end remotest from the elongated contact; a third contact for concurrently engaging the elongated contacts; and means for producing relative movement between the third contact and the elongated contacts, the leaf spring 40 parts twisting in opposite directions through said shank so that, while said relative movement takes place, relative lateral displacement between the pairs of end portions of the elongated contacts will take place in opposite 45 directions.

7. An electric switch comprising a pair of juxtaposed, spaced elongated contacts, a third contact for electrical connection with the pair of contacts by concurrently engaging 50 them; means for producing relative movement between the pair of contacts and the third contact, and torsionally resilient arc-shaped bracket members joined to an intermediate part of said elongated contacts to 55 permit relative lateral displacement between the elongated contacts while minimizing the relative lateral displacement of the bracket members.

In testimony whereof I hereto affix my signature.

HARRY E. NORVIEL.
